UNITED STATES PATENT OFFICE.

GEORGE FREDERICK JAMES AND IVAN E. SMITH, OF NEW YORK, N. Y.

ATTACHMENT FOR STOVES.

1,373,737.

Specification of Letters Patent. Patented Apr. 5, 1921.

Application filed August 14, 1920. Serial No. 403,557.

To all whom it may concern:

Be it known that we, GEORGE FREDERICK JAMES and IVAN E. SMITH, citizens of Great Britain, and residents of New York, in the 5 county of New York and State of New York, have invented certain new and useful Improvements in Attachments for Stoves, of which the following is a specification.

Our invention relates to an attachment 10 for gas and oil stoves, and the invention consists mainly in a spiral and horizontally fluted structure, located in the space above the burner whereby the upward currents of heated air are retarded and deflected as 15 hereinafter set forth.

The invention also consists in the specific construction and combinations as hereinafter described and pointed out in the claim.

In the accompanying drawings to which 20 reference is made and which form a part of this specification:

Figure #1 is a sectional elevation of an oil stove showing, in side elevation, our invention applied thereto and

25 Fig. #2 is a sectional plan view taken on the line 2—2 of Fig. #1.

In the drawings "3" designates an oil stove of the usual or any approved construction having a lid "4" which may be removed, 30 and a perforated top "5". Within the stove is held our draft deflecting device "6" which by preference is suspended from the top "5" by a spider "7", bolt "8" and nut "9", but which may be held in place by any other 35 suitable means. The said draft deflector is, by preference, made of a single strip of sheet metal and is annular and spiral in

form having a central passage "10", and the inner edge of the spiral has the formation of flutes "12" which are radial and which diminish in depth from the inner to the outer edge of the spiral so that while the metal 40 retards the draft and retains the heat, the upward currents of air are diversified by the flutes. Furthermore by fluting a maximum 45 amount of metal is involved which becomes heated and thus retains and makes available a large amount of heat. The operation of forming the flutes of itself produces the annular and spiral formation so that a single 50 operation upon a straight, narrow, strip of sheet metal results in the complete device.

As here shown the lower volute is soldered 55 at "13," to the body of the stove, it being deflected at that point to make contact with the stove thus staying the device, making the whole structure stable.

Having thus described our invention what 60 we claim as new and desire to secure by Letters Patent is:

The combination with the body of an oil 65 or gas stove of a draft retarding and deflecting device suspended in the combustion chamber the same being in annular volute form the spirals being radially fluted and the flutes diminishing in depth from the inner to the outer edge, substantially as shown and described.

GEORGE FREDERICK JAMES.
IVAN E. SMITH.
